UNITED STATES PATENT OFFICE.

CHARLES E. CHITTENDEN, OF ECORSE, MICHIGAN.

HOOP-CUTTING MACHINE.

SPECIFICATION forming part of Letters Patent No. 239,730, dated April 5, 1881.

Application filed October 18, 1880. (No model.)

To all whom it may concern:

Be it known that I, CHARLES E. CHITTENDEN, of Ecorse, in the county of Wayne and State of Michigan, have invented an Improvement in Hoop-Cutting Machines, of which the following is a specification.

My invention relates to hoop-cutting machines; and it consists in the peculiar process and construction of a machine for dividing a plank into hoop-blanks, each of sufficient width to make two beveled hoops, by means of suitable cutters arranged alternately in two cutter-heads, which blanks are reversely inclined and received by guide-rolls and a plate having reversely-inclined corrugations, which securely hold the blanks and turn them into a diagonal position to be sawed into beveled hoops by a series of circular saws, as herein-after more fully set forth.

20 Figure 1 is a longitudinal section of my improved machine. Fig. 2 is a vertical transverse section in front of the cutters. Fig. 3 is an end view of the cutter-head and cutters. Fig. 4 is an end elevation of the plank after it has been subdivided into cants, the dotted lines showing the lines of division or resawing, to make each cant into beveled hoops. Fig. 5 is a similar view, showing the manner of presenting the cants to a series of vertical 25 rotary saws, so that the cants will be converted into beveled hoops. Fig. 6 is a cross-section of one of the cutters *d*.

30 In the accompanying drawings, which form a part of this specification, A represents a suitable frame, adapted to carry the operating parts.

B are a pair of feed-rollers, between which the plank to be operated upon is fed to the cutters.

40 C C' are two cutter-heads suitably journaled in or to the sides of the frame, the former below and the latter above the top of the frame, each operating upon opposite faces of the plank. These cutter-heads and the cutters attached thereto being alike, the description of one will be sufficient. The head itself is rectangular or polygonal in form. To opposite faces of this head are secured the cutters by means of set-screws *a*, passing through slots *b* in the 45 shanks *c* of the cutters *d*, so that the cutters may be adjusted to various thicknesses of

planks. These cutters each taper from base to point, and, being concave in cross-section on their cutting-faces, have two cutting-edges, one on each side. To the intermediate faces 55 of the cutter-head there are adjustably secured, as already described, the cutters *e*, the ends of which present, when in position, a series of concave cutters designed to cut a series of convex surfaces, as shown in Fig. 2. The 60 cutters *d* are designed to cut nearly through the plank presented to them from below and above, and the two heads are so arranged that the cutters *d* on the one head, when in operation, will overlap the like cutters upon the 65 other head—that is, the cutters of one head, cutting from below, cut one side of the cant, while the cutters of the head cutting from above cut the opposite side of the cant, both sides being parallel. As these cutters do not 70 cut clear through the plank, others are required. These are the cutters *e*, which round off each corner of the cant, and in so doing complete the division of the plank.

The above description of the construction 75 of the cutters by means of which a plank is divided into a series of separate slats or cants with rounded edges forms no part of this application, but will hereafter form the subject-matter of a separate application for Letters 80 Patent.

D is a pair of fluted feed and guide rolls, the corrugations of which are such that they fit the rounded edges of the cants, as shown in Fig. 4. These rolls present in the progressive movement of the cants such cants to the corrugated plate E, (or this may be a corrugated roller,) as shown in Fig. 5, adapted to turn such cants into the diagonal positions shown. A roller, F, the corrugations of which 90 are precisely like those of the guide-plate E, and set so that the wider tongues of the latter are presented opposite the narrower tongues of the former, assists in holding the cants in the last position described, and they are then 95 presented to a series of circular saws, G, set vertically on an arbor parallel to the top of the frame, by which the cants are resawed in vertical lines, said lines being diagonal to the parallel sides of the cants.

100 It will be observed that the rolls D, plate E, and roll F have reversely-inclined corruga-

tions separated by alternating high and low ridges which correspond to low and high ridges in the opposing rolls or guides.

What I claim as my invention is—

5 1. The process herein described of forming hoops with beveled edges, consisting in first dividing a plank into a series of separate parallel cants with rounded edges by means of cutters, then introducing said cants each into 10 opposite corrugations in parallel rollers or guides, and giving each cant separately a twist, and finally subjecting each cant thus twisted to the action of a separate saw, to divide it diagonally and lengthwise, the whole 15 operation being performed continuously in one machine, by mechanism substantially as described.

2. In a hoop-cutting machine, the combination, with the cutter-heads C C', carrying cut-

ters d e, arranged alternately in the cutter-heads, of the rolls D, having reversely-inclined corrugations, the extensions on one side lying opposite smaller extensions on the opposite side, substantially as described, and for the purpose set forth.

25 3. In a hoop-cutting machine, the combination, with the cutter-heads C C', carrying cutters d e, arranged alternately in the two cutter-heads, of the rolls D F and spreader-plate E, having reversely-inclined corrugations, the 30 extensions on one side lying opposite smaller extensions on the opposite side, and circular saws G, one for each cant, substantially as described, and for the purpose set forth.

CHARLES E. CHITTENDEN.
